UNITED STATES PATENT OFFICE.

LEWIS T. HOUGHTON, OF WORCESTER, MASSACHUSETTS.

THREAD GUIDE FOR WINDING MACHINES.

Application filed February 19, 1924. Serial No. 693,906.

To all whom it may concern:

Be it known that I, LEWIS T. HOUGHTON, a citizen of the United States, residing at Worcester, in the county of Worcester and 5 State of Massachusetts, have invented a new and useful Thread Guide for Winding Machines, of which the following is a specification.

This invention relates to a thread guide 10 for use in winding or tubing thread. As these packages are wound, the thread forms a path similar to the thread of a screw, the tube or package revolving and the thread guide moving along the package. The 15 thread path resembles a hyperbolic curve. The ends of the package are built up at right angles to the length of the tube without any support or flanges. It is necessary that the guide should hold the thread closely to prevent sidewise movement and lay the threads in place. If the thread is held 20 properly by the guide, the ends of the package are built up straight and square. When the guide becomes worn or grooved so 25 that the thread is not held in place, it results in an imperfect package, especially at the ends. The passage of the thread through the guide cuts and grooves the guide in a short time and it is thrown away. With 30 the sized or glazed thread, the grooving is a matter of weeks.

An object of this invention is to form a guide with a minimum finished surface between the guide and thread package without 35 expensive machining or cutting away of useless surface and its finishing. This finished surface in this invention is determined by the thickness of the material the guide is made of.

40 The principal object of this invention is to revise the manufacture of these guides in such a way that they can be made without the expensive finishing operations that have to be used in making the guides in present use, so that the inner surfaces of the 45 V-shaped guiding grooves can be rapidly and inexpensively made on the blank, and there will be no necessity whatever of performing any finishing operations in the V 50 itself after the V is formed. This is an extremely important feature because the making and finishing of the present day guide is very expensive, and I am able to produce guides in this way at a greatly reduced 55 cost.

Another important feature of the invention consists in making the guide reversible, which is particularly easy in connection with the form of guide that I use, and in keeping the entering thread out of contact with the alternate or reverse face of the guide at all times, so that only one face is worn at a time by the passage of the thread. When the delivery side of the guide is 60 grooved so that it cannot be used any longer 65 the guide can be reversed and the other unworn side used. This doubles the life of the guide and halves the first cost of a single guide.

Reference is to be had to the accompanying 70 drawings, in which

Fig. 1 is an elevation of the traverse mechanism and tube support for a winding machine with a holder and thread guide constructed in accordance with this invention located thereon; 75

Fig. 2 is an end view of the same;

Fig. 3 is a plan of a part of it;

Fig. 4 is a front view of the top of the holder and guide; 80

Fig. 5 is a side view similar to Fig. 2 showing the thread coming in from below instead of above as in Fig. 2;

Fig. 6 is an edge view of a blank of metal 85 from which the thread guide is to be made; and

Fig. 7 is a transverse sectional view thereof.

In the process of tubing thread, a V-shaped slot for guiding the thread has 90 proved to be the most satisfactory. These V slots are machined from a solid piece. They are very expensive to make, especially the finishing of the V-slot or thread path. As the thread leaves the guide slot 95 it passes between the guide face and the tube or thread package and is wound on the tube. The thread is pressed against the tube by the guide with sufficient force to form a hard package, also to prevent any 100 sidewise movement of the thread by the traverse movement of the guide as it passes from end to end of the package. It is also desirable that only a minimum surface of 105 guide should bear on the thread as it leaves the V slot to press the thread against the tube. For this reason the surface of the guide is rounded off on its front surface, thereby preventing the guide from bearing 110 on the adjoining thread so as to displace it,

especially when the guide is at the ends of the tube, and cause an imperfect or rounded end of the thread package instead of a straight square end that is desired. The 5 thread will eventually cut and groove the guide so that the thread is not pressed against the tube with the desired force. When this occurs, a new guide must be installed. As this grooving is inevitable and 10 frequent it causes a great expense.

My device is made without expensive machining and polishing and is quickly replaced or reversed as may be. As this V 15 guide can be manufactured and installed 15 for $\frac{1}{6}$ of the present cost it results in a great saving.

With the old V-shaped guide, when the angle of the V is as acute as is required, the operation of forming the V angle is quite 20 expensive and to give it the necessary surface finish without enlarging the delivery slot, adds very materially to the expense of manufacture. In fact, heretofore, this V slot could not be made with a sufficiently 25 acute angle. The V slot for the thread must be as narrow at the trough of the V as possible so that the sidewise motion of the guide from end to end of the tube cannot materially change the position of the thread as it 30 is laid on the tube.

In tubing thread it is delivered to the guide from below or above according to the package of thread that is to be tubed. When the thread is delivered from above, the present 35 practice requires a special guide of greater cost. The guide as shown and described in this specification, tubes the thread from above or below without any change or adjustment.

40 I overcome some of these difficulties mentioned by making my V guide of a strip A of metal with rounded edges and finished all over in the process of manufacture. This long strip is bent by bending dies into the 45 V shape. As these are not cutting dies they do not spoil the previously finished surface or roughen it in any way. They also make all the guides uniform and accurate. Therefore the rounded edge surface that presses 50 the thread against the tube or package can be made of a minimum extent and the V can be formed in a very acute shape so that the thread is prevented from being forced out of position at the ends of the tube and 55 can be laid accurately, thus producing a square ended tube as stated. Furthermore, the surface that presses on the tube may be predetermined by the thickness of the steel blank before it is bent or forged. This contributes to the same result. It is obvious 60 that the wearing of the guide will eventually allow side movement of the thread and its lateral displacement. Therefore no matter how made, these guides must be replaced as they become worn which consti-

tutes a great expense. A guide lasts only a few weeks. In my guide, the cold forged or bent V is made with the rounded edges of the stock in their original rounded condition and with their final finish before 70 forging. Thus the minimum surface presses the thread on the tube and all the expense of polishing or finishing a machined V guide is eliminated. The only finishing I do is that obtained in a tumbling barrel. I also 75 save the stock lost in machining a V guide, that is, turning or milling it.

The cold forging does not roughen the finished surface of the steel and no parallel 80 grooves and ridges are left on it as would be the case if the guide were stamped out of sheet metal by cutting dies. Also, as stated, the finish that would be required in that case is eliminated. I make the V guide of the previously rolled stock having in its 85 original or blank condition its opposite surfaces parallel with each other. These surfaces are not distorted in that respect when the V is formed as the strip is forced into the V shape while cold.

I prefer to apply my invention to the usual mechanism for traversing the thread back and forth to wind it on a tube T or the like to form the thread package P above referred to. I have shown the usual traverse rod 10 at the bottom of the traverse frame 11. The holder 12 is fixed to the rod by a screw 13. The holder has a clip 14 for engaging over the upper edge of the transverse frame 11.

I form the holder 12 with its front side shown in Fig. 1 a good deal of the ordinary shape, except that the upper ends 15 of the holder extend up parallel with each other to the top of it. The main body of the holder is provided with two opposite but dissimilar wings 16 and 16^a which are bent back from these ends 15 parallel with each other. A bolt 17 is located at the rear through these wings and screws into one of them so as to hold them firmly together. This bolt, of course, has a smooth surface and it has a definite location as will appear. It is designed to perform the above mentioned object and to guide the thread into 110 the guide at the proper elevation. Behind it is another rod 18 supported preferably by the wing 16 and located parallel with the bolt 17 and spaced a little behind it and below it. This is designed to receive the 115 thread as shown in Fig. 2 as it comes down from above and force it into contact with the upper surface of the bolt 17 and direct it into the guide.

The top edges of the two wings are provided with similar projections, dove-tails, or other means 19 for engaging similar slots or grooves in the ends 21 of the guide 20 and locating the said guide on the top surfaces of the two wings. It will be seen, there- 120 125 130

fore, especially by reference to Fig. 3 that by tightening up the bolt 17 the guide 20 is clamped firmly to the two wings or rather the projections 19.

5 When the wear gets deep enough so that the guide has to be removed I unscrew the bolt 17 so as to release the guide, pull the guide out of its place on the holder, reverse it, and put it back again and then screw up 10 the bolt. This reversal, of course, doubles the life of the guide. By placing the bolt 17 in the position shown, the thread is kept from wearing the rear portion of the guide at all times, so that when the guide is reversed 15 the surface that is used as a guiding surface is entirely fresh and unworn and ungrooved in any way. The thread can be brought to this guide either from below as shown in Fig. 5 or from above as 20 shown in Fig. 2.

The ordinary V-shaped guides used in tubing have circular convex surfaces for engaging the tube or package and the V is cut in this. The delivery of the yarn therefore 25 is at the point where the inclined sides of the V-shaped groove meet. This point of meeting projects beyond the rest of the convex surface of the guide and receives and sustains the entire pressure of the tube or 30 package against the guide as the yarn moves from end to end of the package. This pressure rolls or pushes the yarn forward beyond its correct vertical position on account of the fact that the delivery and pressure 35 points are the same.

By referring especially to Figs. 3 and 5 it will be seen that in my case two points on the rounded edges of the guide and at 40 opposite sides of the V portion bear on the tube T. However when one layer of thread has been wound on the tube to form the package it will be understood that in advance of the guide there is a slight clearance 45 equal to the thickness of the thread. The bearing point at the side of the guide which rests on the thread that has just been laid necessarily holds the opposite point away from the package a distance equal to the thickness of the thread. There is always 50 one more thread or layer of thread on one side of the guide than on the other and this necessitates the bearing on the thread of the point at one side of the V and the spacing from the thread of the corresponding point 55 on the other side of the V. On this account the liability of the guide forcing the end layers of yarn out of position at the end of the tube is overcome. The forward side of 60 the guide which might do that is not actually in contact with the thread. As the guide comes back along the package in the other direction, the bearing point on the inner edge of the guide which previously rested on the thread now is in advance of the 65 thread and it is the other side which re-

ceives the pressure, so that the conditions are the same except that the bearing point is reversed. The side of the V guide at the rear is always the one to bear on the thread and apply pressure to it to wipe it forward 70 on the tube and hold it in position. This results in more even laying of the thread and removes the possibility of forcing the thread out of position especially at the end of the tube which would cause unevenness in 75 the vertical face of the tube.

The alternating points of engagement with the package provided by this device as described above are of special importance. The support or bearing point of the guide 80 against the tube is placed on one side of the V and then on the other as the direction of travel changes. Heretofore this point has always been central and it was always the same in both directions of travel. In this 85 case the point of support is always back or toward the center of the tube. Heretofore the pressure has always been the same at the end of the tube or package as it is elsewhere along it, but in this invention the pressure 90 is released from the yarn as it is laid at either end of the package so there is no pressure on the last thread to roll it over the vertical face of the tube, thus the yarn is 95 not only applied on the tube just where it is designed to be but all tendency to force it over at the end and spoil the flat surface of the end of the package is eliminated.

It is to be noticed also that this cold forged guide has its two bearing points on 100 opposite sides of the yarn in a vertical plane which plane is geometrically tangent to the circumference of the package or tube. This prevents the traverse motion forcing the thread side-ways in either direction and insures positive delivery of the yarn to the tube in the same vertical plane at each turn of the traverse. These two surfaces are 105 never bearing on the yarn package at the same time and wear on each is half what it has been in the old forms and the life is doubled.

In all the previous cases with which I am familiar the yarn is drawn through the guide slot from one side to the other in a 110 horizontal direction substantially radially with respect to the yarn package. Therefore the thread comes toward the package in a radial direction and then suddenly turns off at right angles at the trough of the V guide 115 in the old forms. There is only one point at which it can leave the guide and enter 120 the package.

In this invention the yarn path is exactly as shown in Fig. 5. The yarn does 125 not come at the package in a radial direction but comes from above. I find in practice that this gives a smooth finish to the yarn. Many devices have been made to obtain a smooth finish, even waxing the yarn has 130

been tried and is now used to a considerable extent. I secure this result without additional mechanism merely by introducing the yarn at an obtuse angle or on a tangent and it accomplishes the purpose better and without employing any waxing devices or other special mechanism. The nearer tangent this angle is the less liability is there of raising the fibres on the yarn as it passes over the edge of the guide on the package. When the yarn passes over a right angled corner or edge the fibres on the yarn are necessarily raised on the convex or outer side. The object of the construction now under discussion is to give the yarn a more obtuse angle to turn about and therefore the fibres will not be raised and the thread comes through in a smooth condition. It is impossible in the old forms of guide to avoid bending the yarn about a right angle corner at the point of delivery and thus raising the fibres on the yarn and roughing it up.

When soft yarn is tubed or wound turning a right angle in its path the short fibres rise on the outer or convex side of the bend leaving the yarn rough and shaggy. When a straight path is maintained these fibres do not have any occasion to rise away from the yarn and the frictional engagement with the vertical sides of the guide smooths the fibres and imparts a real finish to the yarn impossible to obtain with other guides even by the use of wax. It has been found in practice that the finish is better on this machine than the wax finish on the ordinary machines on the market.

In this guide, the delivery point receives the pressure of the tube, relieving the yarn from the tension that is encountered in drawing the yarn over a bearing surface under pressure. This relieves the pressure at this point and permits the regulating of the tension at another point and does not raise the yarn fibres on the convex side of the yarn.

If desired my guide can be bent so that the V at one side is wider than that at the other so that when it is reversed it will be suited for a change in size of thread.

I have not described the means for holding the holder and guide up against the package as that is well known in this art, nor have I shown the means for traversing the traverse bar or rotating the spindle as this invention does not relate to those features and can be employed with any variety of these devices.

Although I have illustrated and described only a single form of the invention I am aware of the fact that modifications can be made therein by any person skilled in the art without departing from the scope of the invention as expressed in the claims. Therefore, I do not wish to be limited to all the details of construction or the exact

order of steps specified, but what I do claim is:—

1. As an article of manufacture, a thread guide for winding or tubing thread comprising a bar of metal of requisite shape size 70 and finish having a V shape with the angle thereof extending across the bar in the direction of its width to provide two flat surfaces converging to form a guide for the thread, whereby the surfaces of the guide 75 are left in their original finished condition and do not require any mechanical finishing thereon.

2. As an article of manufacture, a thread guide for tubing consisting of a flat bar of metal having V shaped form with the trough of the V having a material width and located at a distance from the end of the bar to provide a thread guide passage 80 and left with its walls of uniform thickness. 85

3. As an article of manufacture, a thread guide for the purpose described formed from a bar of smooth surfaced metal, one original external smooth surface of said bar of metal constituting two co-operating and converging 90 flat surfaces for guiding the thread between them.

4. As an article of manufacture, a thread guide for the purpose described formed from a piece of smooth surfaced metal, the metal 95 having a substantial breadth being shaped into a V-form to constitute the guiding groove having converging surfaces of the breadth of the original piece of metal for receiving the thread against them, said surfaces retaining the finish and smoothness of the original blank. 100

5. As an article of manufacture, a thread guiding device for tubing thread comprising a guide holder and a guide for the thread 105 mounted thereon and formed of a bar of flat stock bent transversely into V-shape to provide a guiding means for the thread.

6. As an article of manufacture, a guiding device for winding tubing packages comprising a guide holder and a guide thereon consisting of a piece of metal originally formed in a wide flat strip round at the edges, the flat surfaces and convex edges receiving their finish in the process of manufacture, said strip being formed of the desired length and being bent into V-shape 115 to provide a guide having wide finished interior surfaces without necessitating any machining operation. 120

7. As an article of manufacture, a guiding means for thread formed from a strip of metal having a finish on its sides and edges and in the form of a V-shaped guide having a trough of substantial width for receiving the thread, whereby the surfaces of the interior of the V are left smooth in the process of manufacture and do not have to be finished after the V is formed. 125

8. As an article of manufacture, a thread 130

guiding device comprising a holder adapted to be carried with the traverse bar of a winding machine and operated thereby and provided with a pair of opposite walls perpendicular to the front of the holder, and a thread guide consisting of a piece of flat stock of V-shape and having its front and rear edges spaced apart and its opposite ends detachably connected with the sides 10 of the holder, whereby said guide can be taken off and reversed and secured back with the other edge in operative position.

9. As an article of manufacture, a thread guiding device for tubing thread comprising a holder and a thread guide having at 15 opposite edges two thread guiding surfaces at a material distance apart detachably mounted on the holder and reversible end to end on the holder to provide a new guiding surface.

10. As an article of manufacture, a V-shaped thread guide reversible edge to edge to provide a new guiding surface, and means for guiding the thread into the guide in such 25 position that there is a long surface of the guide under the thread which it does not engage, whereby when the guide is reversed the new point of delivery will have a fresh unworn surface.

30 11. As an article of manufacture, a thread guiding device of V shape for tubing thread comprising a holder and a thread guide detachably mounted thereon and reversible end to end on the holder to provide a new guiding surface, and means carried by said 35 holder for guiding the thread into the guide in such position that it does not engage the trough of the V except adjoining the point of delivery of the thread and leaves the 40 larger part of the V shaped groove unworn, whereby when the guide is reversed the new point of delivery will have a fresh unworn surface.

45 12. In a thread guiding device for winding thread on a tube, the combination of a holder adapted to be carried by the traverse bar, a thread guide detachably and reversibly mounted on the holder and having walls of uniform thickness and of V-shape, and a 50 rod across the holder at the entrance side of the V for leading the thread out of contact with the bottom of the trough of the V when it enters the guide, whereby the guide may be taken off and reversed and the new guiding surface at the delivery end of the guide will be fresh and unworn.

55 13. In a thread guide of the class described, the combination of a holder, a guide carried by the holder consisting of a bar of metal of uniform thickness throughout of a 60 shape to furnish a V guide at a distance from the ends thereof, and means on the holder for lifting the thread out of contact with the bottom of the trough of the V as it enters the guide, whereby the sides of the

V will guide the thread down into the trough at the delivery side of the guide and prevent its displacement therefrom.

14. In a thread guiding device of the class described, the combination of a holder having a rear surface adapted to be received against the front of the traverse frame and provided with two transverse wings extending backwardly therefrom parallel with each other, a V shaped thread guide formed of metal stock of uniform thickness detachably connected with the upper sides of said wings and resting thereon, a rod carried by said wings and extending across the rear of the V guide and projecting above the bottom of the trough thereof to keep the thread out of the bottom of the trough at the entrance side of the guide, and a bar supported by one of said wings and extending beyond the other for receiving the thread under it to guide it over the rod.

15. In a thread guiding device of the class described, the combination of a holder having a rear surface adapted to be received against the front of the traverse frame and provided with two transverse wings extending backwardly therefrom parallel with each other, a V shaped thread guide formed of metal stock of uniform thickness detachably connected with the upper sides of said wings and resting thereon and a rod carried by said wings and extending across the rear of the V guide and projecting above the bottom of the trough thereof to keep the thread out of the bottom of the trough at the entrance side of the guide, and constituting clamping means between the two wings to adjust them with respect to each other and hold them in position clamped against the guide to hold it in position.

16. In a thread guiding device of the class described, the combination of a V-shaped thread guide of uniform thickness, and a rod extending across the rear of the V-guide and projecting above the bottom of the trough thereof to keep the thread out of the bottom of the trough at the entrance side of the guide.

17. In a thread guiding device of the class described, the combination of a V shaped thread guide, a rod extending across the rear of the V guide and projecting above the bottom of the trough thereof to keep the thread out of the bottom of the trough at the entrance side of the guide, and a bar extending beyond the other for receiving the thread under it to guide it over the first named bar.

18. In a thread guiding device of the class described, the combination with a V-shaped guide having wide slanting surfaces converging to the trough of the V and adapted to engage the yarn package on its edge, and means for guiding the yarn into the guide at such an angle that the yarn will not touch

the trough of the V back of the delivery point and will engage the V along the sides of the trough if at all and will come into contact with the yarn package over a surface of the guide at one side of the V.

19. As an article of manufacture, a yarn guide comprising a V-shaped piece of metal having a rounded edge on the delivery end thereby providing a semi-circular convex path over which the yarn passes in direct contact with the package on which it is being wound so that the point of delivery of the yarn to the package under traverse motion is at one side of the trough of the V instead of at the trough.

20. A guide for tubing or winding yarn

having two separated convex supporting surfaces at its sides in the same plane for holding the yarn against the package and means for holding the yarn out of contact with the bottom of the guide back of said plane.

21. A yarn guide having convex edges in position for alternating in support of the yarn package during the traverse motion so that the forward edge is always held away from the yarn package, thereby relieving the end strands of the yarn on the package from pressure.

In testimony whereof I have hereunto affixed my signature.

LEWIS T. HOUGHTON.
